Victor J. Evans
ATTORNEY

UNITED STATES PATENT OFFICE.

THOMAS R. MACMECHEN, OF NEWARK, NEW JERSEY.

PROPELLER.

Application filed July 8, 1921. Serial No. 483,288.

To all whom it may concern:

Be it known that I, THOMAS R. MACMECHEN, a citizen of the United States, residing at Newark, in the county of Essex and State of New Jersey, have invented new and useful Improvements in a Propeller, of which the following is a specification.

This invention relates to propellers or fans and analogous devices used for purposes of 10 propulsion or exhaustion and it has for its primary object the provision of a novel form of propeller or fan in which the blades are tangentially and rigidly mounted relative to their hub or axis of rotation.

15 Another object of this invention is the provision of a propeller or fan characterized by blades of uniform concavo-convex cross section throughout their entire length which are so mounted relative to the hub 20 that when in rotation they create what may be termed open ended buckets, open not only at each end but open on the inner side or surface facing the axis of rotation.

25 A further object of this invention is to provide a propeller or fan by the use of which a practically constant consumption of the particular power employed for its rotation is maintained no matter at what velocity or revolutions per minute it may be 30 rotated.

35 A still further object of this invention is to provide a device of the kind referred to in which surface friction tending to create slippage is to all practical intent eliminated, 40 whilst when in operation there is no appreciable evidence of moment of inertia or any radius of gyration.

With the foregoing fundamental objects in view my invention consists essentially of 45 a propeller or fan having blades of uniform concavo-convex cross section and diagonally opposed hyperbolically curved edges, said blades being tangentially and rigidly supported relative to their hub or axis of rotation.

In the further disclosure of the invention reference is to be had to the accompanying sheet of explanatory drawings constituting a part of this specification and in which 50 like characters of reference designate the same or corresponding parts in all the views:

Figure 1 is an end view of a propeller or fan embodying my present invention.

Figure 2 is a side view of the same; and,

Figure 3 is a detail view of one of the 55 blades and its supporting members detached from the propeller hub.

Referring more particularly to the views the numeral 10 designates a tubular hub which is appropriately provided with end 60 flanges 11 between which and cap flanges or washers 12 the ends of the blade supporting arms 13 are securely held by bolts or set-screws 14 as later on explained.

Each blade 15 is conveniently though not 65 essentially made from a sheet metal blank of uniform thickness and moulded or bent to concavo-convex throughout its entire length and said blade is fashioned with diagonally opposed relatively parallel edges 16, 16, and other diagonally opposed edges formed in hyperbolic curves 17, 17. Each blade 15 is also suitably fashioned so that the tips 18, 18, thereof are turned directly 70 central relative to its axial length in the 75 manner described in prior United States Patent #1,372,755.

Welded or otherwise appropriately attached to or formed integral with each blade 80 15 are a pair of the opposed supporting arms 80 13 the free ends whereof are suitably fashioned to provide segmental ends 19 having notched out parts 20 adapted to snugly 85 abut the bushing 21 of the propeller hub 10; and it will be clearly seen on an examination 90 of Figures 1 and 2 more particularly that the three segmental ends 19 at each side of the hub 10 snugly abut each other about the bushing 21 and further that they are firmly clamped between the end flanges 90 11 and cap flanges 12 by the bolts or set screws 14.

When a propeller constructed as above set forth is employed for separation purposes it is to be observed that the three or 95 more blades 15 being disposed equi-distantly around the hub 10 and due to their peculiar formation and manner of mounting or tangential disposition relative thereto they will be in a measure resiliently supported, and when in rotation will create what may be termed open-ended buckets, open not only at each end but also on the inner side or surface facing the axis of rotation, and I wish here to particularly point 100 out that I have discovered by actual tests that my equi-potential propeller when in use permits of a slight variation or reduc- 105

tion in the pitch due to the resilient difform movements of the buckets. Still further I have discovered that when my invention is employed as a fan the temperature of the air entrained thereby—as read from a thermometer—shows absolutely no rise whereas the air entrained by an ordinary fan invariably shows a rise in temperature.

Furthermore it is to be remarked that the exterior of the buckets formed by the rotating blades 15 and the mountings thereof experience no obstruction to their passage through the air or other element, produce no side currents, nor any audible sound or vibration, nor any increase in temperature; and are in fact equi-potential surfaces.

It is to be most particularly remarked that when my improved propeller is used as such that is to say for purposes of propulsion or ventilation the supporting of the blades 15 relative to the hub 10 must be rigid; that is to say, there must not be any resilient tendency existent.

Whilst I have shown and described one practical embodiment and referred to application of my present invention which is particularly adapted for service as a ventilating fan, or airship propeller; the same is not to be construed as conclusive as it will be perfectly obvious that heavier types and other forms of the blades 15 may be forged or cast on identical lines for use on the propellers of aquatic vessels and similarly the method of mounting said blades relative to the hub 10 may be other than that specifically described; and I wish it clearly understood that I do not limit or restrict myself in any way to the specific embodiment disclosed but deem myself at liberty to make such changes or variation

as fairly fall within the scope of the appended claims.

Having described my invention what I claim as new and desire to secure by Letters Patent is:

1. A propeller comprising a hub for attachment on a rotatable axis, and blades rigidly supported in tangential relation thereto, each of said blades being formed to provide opposed surfaces of uniformly concavo-convex cross section throughout their length and having the tips thereof spirally twisted into a line directly central thereof. 50

2. A propeller including a hub for attachment on a rotatable shaft, and blades rigidly supported in tangential and oblique relation relative to the longitudinal axis of said hub, each of said blades having a cross sectional surface of uniform curvature and being formed with opposed parallel and curved edges with the curved edges constituting continuations of the parallel edges, and said blade being also spirally twisted at its medial portion to have the tips thereof lie in a longitudinal plane and curved toward each other. 55

3. A propeller including a hub for mounting on a rotatable shaft, blades disposed about said hub in equi-spaced relation, each of said blades being formed to provide opposed surfaces of uniformly concavo-convex cross section throughout their length and having the tips spirally twisted into a line directly central thereof, and opposed arms rigidly supporting each blade, one of said arms being attached at one end and the other arm at the other end of the hub. 60

In testimony whereof I affix my signature.

THOMAS R. MACMECHEN.
